(57) **CLAIM**

The ornamental design for a faceted reflector, as shown and described.

DESCRIPTION

FIG. 1 is a perspective view of the new design, with the broken line showing for illustrative purposes only and forming no part of the claimed design;

FIG. 2 is a top plan view of the new design;

FIG. 3 is a right side elevational view of the new design, the left side elevational view being a mirror image thereof;

FIG. 4 is a front elevational view of the new design;

FIG. 5 is a rear elevational view of the new design; and,

FIG. 6 is a bottom plan view of the new design.
